BY *Leinson & Sonnenfeld*
ATTORNEYS.

UNITED STATES PATENT OFFICE.

ROBROY C. HOAGLAND, OF CORTLAND, NEW YORK, ASSIGNOR TO THE BREWER-TITCHENER CORPORATION, OF CORTLAND, NEW YORK, A CORPORATION OF NEW YORK.

AUTOMOBILE TOP.

Application filed February 18, 1919. Serial No. 277,782.

To all whom it may concern:

Be it known that I, ROBROY C. HOAGLAND, of Cortland, in the county of Cortland, in the State of New York, have invented new and useful Improvements in Automobile Tops, of which the following, taken in connection with the accompanying drawings, is a full, clear, and exact description.

This invention relates to certain improvements in vehicle tops.

The practical manufacture of vehicle tops has divided itself into two distinct commercial lines—first, the bow-socket construction utilizing tubular sheet metal bow-
15 sockets and short wooden bows, and second, the slat-iron construction utilizing slat-irons as a skeleton structure and long wooden bows having their end portions secured to and extending along and substantially cover-
20 ing the slat-irons.

The latter construction has been far more expensive to manufacture than the former due to the cost of obtaining suitable material and then properly treating the same
25 to form long wooden bows having portions quite necessarily finished for design or ornamental purposes as the same are exposed to view in the completed top structure.

Further, the loss in manufacture due to imperfections in the material, poor workmanship, mistakes and deformation by climatic and humidity variations is relatively great.

It is also of importance that the manufacture of the long wooden bow slat-iron construction has not lent itself to quantity production but has practically remained a hand performed operation for the skilled wood worker or artisan.

Altho, therefore, this character of top structure is at least preferable from an ornamental or design standpoint, its use has been materially restricted by the difficulty and expense of manufacture.

The object of the invention is, therefore, to produce a vehicle top having practically all the advantages of the long wooden bow slat-iron construction including its ornamental and design features, while largely avoiding the difficulties and high expense of manufacture as at present carried on.

The invention takes form in a slat-iron frame work combined with wooden side braces adapted to be formed of suitable material finished in any desired way and at-

tached to the outer side of the slat-irons so as to cover the same and extending a sufficient distance along the slat-iron so that their upper ends are hid by the depending side or quarter of the top fabric. 60

The slat-irons extend beyond the upper termination of the side braces and a suitable bow of preferable relatively low grade material may have its ends secured to opposite slat-irons so that said ends abut against the upper ends of the side braces and form a substantially symmetrical continuation thereof.

The bow, as stated, may be the usual ordinary wood bow of the bow-socket top construction, suitably covered with fabric in the ordinary manner thereby avoiding any substantial change in present accepted methods of manufacture. 70

A top structure so manufactured has substantially all the advantages of the long bow slat-iron construction without the attendant difficulty and expense of manufacture. 75

Further the construction of this invention lends itself to quantity production. The manufacturer may construct the usual slat-iron frame work and attach the finished wooden side braces thereto, and sell the same in that form, allowing the manufacturer of the top to apply the usual wooden bows in 85 much the same manner as manufacture is carrying on to-day, in the quite general use of the bow-socket top construction.

Other objects and advantages will appear from the following description taken in connection with the accompanying drawings in which,

Figure 1, is an elevation of one side of a top structure, it being understood that the two sides are of substantially the same construction. 95

Figure 2, is a cross-section on line 2—2 Figure 1.

Figure 3, is a cross-section on line 3—3 Figure 2.

Figure 4, illustrates a means for connecting the upper end of a side brace to the abutting end of the bow to prevent relative lateral movement of the parts. 100

Figure 5, shows a slightly modified form of slat-iron in that the forging disclosed in the former figures is omitted.

As previously intimated the top structure of this invention is adapted to be used in connection with automobiles, motor boats 110

and similar vehicles, in some cases requiring a top of considerable length and which may embody any suitable or desirable number of bows and supports for the same, the specific 5 illustration of Figure 1, showing four bows, a rear bow —1—, a main bow —2—, a front bow —3—, and an auxiliary bow —4—, these bows being respectively carried by slat-irons —5—, —6—, —7—, and —8—.

10 A description of the construction of the main bow —2— and the construction of its supporting parts will serve as a description of the construction and arrangement of each of the other bows and its supporting parts.

15 The slat-irons —6— comprise in this illustration the forgings —7— preferably integrally united with the flat bodies —8— of the slat-irons, the upper ends —9— of which are curved or arched inwardly for contact 20 with and securement to a somewhat U-shaped bow —10—, bridging and connecting the opposite slat-irons. The ends of the bow —10— terminate at a point above the lower edge of the side or quarter of the top fabric 25 which is secured to the bows and is indicated in dotted lines Figure 1.

Wooden side braces —11— are secured upon the outer face of bodies —8— of the slat-irons and have their upper ends 30 abutting against the respective lower ends of the bow —10— and preferably form a substantially symmetrical continuation of the bow. These wooden braces —11— may be formed of desired shape and are preferably 35 of sufficient width to entirely cover the body of the slat-irons and may be secured thereto by means of screws and preferably extend downwardly to the points adjacent the lower ends of the slat-irons and abut against 40 the parts —12— of forgings —7—, which parts project laterally and outwardly from the body —8— of the slat-irons —6— and are shaped to form a substantially symmetrical continuation of the wooden braces 45 —11—.

The wooden side braces —11— may be formed of suitable high grade material finished in any desired manner, either merely to bring out the natural grain of the wood 50 as by varnishing or the like or by the application of stain to represent other characters of wood or material.

The upper ends of the wooden side braces may preferably terminate at substantially 55 the base of the curved part —9— of the slat-iron and this portion —9— lying beyond the side braces may be provided with suitable openings for the reception of screws —13— to secure the bow to its respective pair of 60 slat-irons. The side braces combined with the bow render the slat-iron construction substantially rigid and of sufficient strength to efficiently support the top structure.

Additional means may be provided for 65 preventing relative lateral movement of the

abutting ends of the bows and side braces and as illustrative of such a means, I have disclosed in Figure 4, a dowel pin —14— having its opposite portions tightly fitted in recess in such abutting ends. Other 70 means such as clamps may be utilized for this purpose.

The bows —10— are preferably provided with a suitable fabric covering as commonly used in the manufacture of the bow-socket top construction, and this fabric may extend beyond the opposite ends of the bow and cover the joints between the opposite wooden side braces and the respective abutting ends of the bow. For the purpose of clearly 75 showing the bows I have omitted illustrating this fabric covering but its application and use will be readily understood without physical illustration or further description.

In Figure 5, I have shown at —15— a slightly modified form of slat-iron combined with a slightly modified wooden side brace —16— in that the forgings —7— with their laterally projecting parts —12— are omitted and the lower ends of the side braces are 80 tapered to emerge into the flat surface of the slat-iron.

It will be understood that my invention is applicable to all forms of vehicle tops, the one illustrated in Figure 1, being merely 85 illustrative of a particular form to which the invention may be applied. In that particular illustration the slat-iron —6— carrying the main bow has pivoted to it link —17—, rule or otherwise stop-jointed to the slat-iron —7—. The slat-iron —8— is pivoted to the intermediate part of link —17— and suitable struts —18— and —19— pivotally connect slat-iron —6— to slat-iron —8— and slat-iron —8— to slat-iron —7—, respectively. This construction is one form 90 of the well known "one man top" and my invention is applicable to all such tops. No one, so far as I am aware, has ever utilized short wooden bows with a socketless 95 construction of top strengthened and ornamented by outwardly facing finished wooden brace members.

Modifications and changes may be made in the details of construction, form and arrangement without departing from the spirit of the invention as set forth in the appended claims.

What I claim is:

1. In a socketless vehicle top, a pair of 100 oppositely disposed slat irons having curved upper ends extending towards each other, a wooden frame member formed of high grade finished material extending from a point adjacent the lower end of the respective slat irons to a point above the lower edge of the top quarter of the top, and a bow bridging the slat irons and having its opposite end connected to the upper curved 105 ends of said slat irons respectively, and its 110

end portions in substantial contact with the upper end portions of the wooden frame members respectively.

2. In a socketless vehicle top, a pair of oppositely disposed slat-irons, a finished wooden brace member secured upon the outer face of each slat-iron and extending from a point adjacent the lower end of the respective slat-irons to a point above the lower edge of the top quarter and a bow bridging the slat-irons and having its opposite ends abutting against respective brace members and forming a substantial continuation of said brace members, means for se-

curing the ends of said bow to the adjacent portions of the slat-irons respectively, and additional means connecting the end of the bow to the end of the adjacent brace member to prevent relative lateral movement of said parts.

In witness whereof I have hereunto set my hand this fourteenth day of February, 1919.

ROBROY C. HOAGLAND.
